CABINET FOR DISPENSING CONES, CUPS, AND THE LIKE

Francis W. Turnbull, Signal Mountain, Tenn.

Application September 13, 1952, Serial No. 21,443

Term of patent 7 years

(Cl. D52—2)

To all whom it may concern:

Be it known that I, Francis W. Turnbull, a citizen of the United States and a resident of Signal Mountain, county of Hamilton, and State of Tennessee, have invented a new, original, and ornamental Design for a Cabinet for Dispensing Cones, Cups, and the like, of which the following is a specification, reference being had to the accompanying drawing forming a part thereof, in which

Fig. 1 is a perspective view of a cabinet for dispensing cones, cups and the like showing my new design when the tray thereof is in the open position; Fig. 2 is a side view of the same on substantially the scale of Fig. 1, when the tray thereof is in the closed position; Fig. 3 is a front view of the same when the tray is in the position shown in Fig. 2; and Fig. 4 is a top view of the same when the tray is in the position of Fig. 1.

I claim:

The ornamental design for a cabinet for dispensing cones, cups and the like, substantially as shown.

FRANCIS W. TURNBULL.
